FLOATING BREAKWATER

Louis Gillasso, New Orleans, La., assignor to The Texas Company, New York, N. Y., a corporation of Delaware

Application July 14, 1939, Serial No. 284,472

3 Claims. (Cl. 61—5)

This invention relates to a floating breakwater and more particularly to a device adapted to break and smooth out waves which would otherwise impinge upon a structure such as a submerged drilling or pumping barge foundation engaged in producing a well in a subaqueous location.

The principal object of the invention is to provide a device of this character which will be simple and inexpensive to construct and which can easily be placed in position and subsequently moved to another location.

In well drilling and other well producing operations in underwater locations, it is common to use as a foundation a submerged barge on which the derrick and other equipment are mounted. In some places it is possible to use mat or piling foundations although these are usually more suitable to shallow waters. Where submerged barges or other foundations are used in open water, it is often difficult to secure a boat to the foundation so as to load or unload equipment and this is particularly true in rough weather since the waves frequently strike and break over the foundation with considerable force.

In carrying out the present invention, a device has been provided for breaking and smoothing out the waves which would otherwise strike the foundation. The device comprises an elongated float member or series of float members anchored to the bottom and extending along the seaward side of the submerged structure. Plate members depending from the floats serve to break up the waves and upwardly projecting fins smooth out those waves which may pass over the floats.

For a better understanding of the invention reference may be had to the accompanying drawing in which:

40 Figure 1 is a longitudinal elevation;

Figure 2 is a plan showing the relative arrangement of the breakwater and a protected structure, while

Figure 3 is a side sectional elevation taken on the line 3—3 of Figure 1.

Referring to the drawing, an elongated, tubular, water-tight float member 10 is designed to have sufficient buoyancy to remain afloat about half submerged in the water. Secured to and depending from the lower surface of the float 10 is a plate 12 preferably of metal. As will be observed with reference to Figure 1, the plate 12 extends throughout substantially the entire length of the float 10 and reinforcing stays 14 secured to the float and also to the plate 12 serve

to stiffen the latter. Secured to and projecting substantially upwardly from the upper surface of the float 10 are a plurality of fins 16, these fins being arranged preferably in parallel rows and extending throughout the length of the float. 5 Suitable anchors 18 are attached to the lower edge of the plate 12 or to one of the reinforcing stays 14 by means of chains or other cables 20.

As shown in Figure 2, three of the float units, A, B and C are attached together end to end by 10 means of suitable cables 22 and the three units are anchored at the seaward side of a submerged barge or other foundation 24.

As will be observed by referring to Figure 3, the depending plates 12 serve to break up waves 15 moving to the left, i. e., toward the foundation 24 while the fins 16 smooth out the waves passing over the float members 10. With this arrangement the waves are so smoothed, even in very rough waters, that there is no trouble or danger 20 in approaching or leaving the foundation 24 or in tying a boat thereto such as for unloading a quantity of drill pipe or other material.

Obviously many modifications and variations of the invention as above set forth may be made 25 without departing from the spirit and scope thereof, and therefore only such limitations should be imposed as are indicated by the appended claims.

I claim:

1. A floating breakwater comprising an elongated water-tight, buoyant member, a plate secured to and depending from said member, reinforcing stays secured to said member and said plate, a plurality of longitudinally extending fins 35 attached to and projecting substantially upwardly from said elongated member so as to aid in smoothing waves passing over said member, and anchor means attached to the lower edge of said plate. 40

2. A device for protecting a well drilling or pumping foundation in a subaqueous location from waves, comprising a plurality of elongated tubular float members disposed end to end, means for flexibly connecting adjacent ends of said 45 members, a metallic plate member secured to and depending from the underside of each of said float members, reinforcing stays connected to said float members and said plate members for stiffening the latter, and anchors attached to the 50 lower edge of each plate member.

3. A device for protecting a submarine well drilling or pumping barge from waves comprising a plurality of elongated tubular float members disposed end to end, means for flexibly connect- 55

ing adjacent ends of said members, a substantially rectangular metallic plate member secured to and depending from the underside of each of said float members, reinforcing stays connected to said float members and said plate members for stiffening the latter, a plurality of substantially upwardly projecting fins secured to the

upper surface of each of said float members, said fins being arranged in parallel rows and extending throughout the length of said float members so as to smooth out waves passing over said float members, and anchors attached to the lower edge of each plate member. 5

LOUIS GILIASSO.
